UNITED STATES PATENT OFFICE.

ANTON SKOFSRUD, OF CHICAGO, ILLINOIS.

REEL OR WINDING-MACHINE.

1,204,597.

Specification of Letters Patent. Patented Nov. 14, 1916.

Application filed July 29, 1912. Serial No. 712,026.

To all whom it may concern:

Be it known that I, ANTON SKOFSRUD, a citizen of the United States, residing at Chicago, in the county of Cook and State of Illinois, have invented certain new and useful Improvements in Reels or Winding Machines, of which the following is a specification.

This invention relates to machines for winding up paper, cloth or other fabric or material, and more particularly to such machines which will automatically wind up and cut off small rolls from a continuous strip of material.

Among the objects of these machines are to provide means whereby the material which is being wound will be accurately measured, regardless of the thickness of the material, so that each of the small rolls will contain as nearly as possible the exact desired amount; to provide means whereby the feed of the machines will be operated by the material which is being acted upon so that if the material is torn or broken, it will stop the further winding action of the machine; and furthermore to provide such novel features of construction and improvements in details as will be more fully described and pointed out hereinafter.

The reeling or winding up of wall paper into small rolls illustrates one of the uses to which this machine is adapted. In the usual manufacture of wall paper the paper from the drying racks is wound into large rolls and then the paper in these large rolls is unwound and wound up into small rolls by means of manually operated spindles. The paper passes through the printing machine at such a high rate of speed that it requires an exceedingly rapid machine to take the paper from the drying racks and automatically roll it into small rolls, and so far as I am aware no machine has been produced which can be operated sufficiently rapid to do this work with the exception of certain machines heretofore patented by me. The present machine is adapted to be operated at a high rate of speed so as to take the paper directly from the drying rack and wind it into the desired size of rolls.

In the accompanying drawings illustrating my invention; Figure 1 represents a front elevation of the lower part of the machine, that is the sides from which the rolls are discharged, parts being omitted or broken away for convenience in illustration;

Fig. 2 is a detail showing the lever for operating the machine; Fig. 3 is a rear elevation with parts also omitted or broken away for convenience in illustration; Fig. 4 is an end view also with parts omitted or broken away; Fig. 5 is a detail of the adjustment for the measuring device; Fig. 6 is a detail of a portion of the measuring and cut-off operating mechanism; Fig. 7 is a sectional view taken on line 7, 7 of Fig. 6; Fig. 8 is a sectional view taken on the line 8, 8 of Fig. 6; Fig. 9 is a plan view of a portion of the apparatus shown in Fig. 6; Figs. 10 and 11 are details of portions of the driving mechanism for operating the spindles and cutting off devices, and Fig. 12 is a detail of the discharge device.

As indicated in these drawings, 15 represents a frame work of suitable design for supporting the various parts, which frame work is provided with suitable bearings for the main drive shaft 16. This shaft may be driven in any desired manner, for instance, by means of a gear 17 which meshes with 65 a pinion 18 on a vertical shaft 19. The lower end of the shaft 19 is provided with a gear 20 which meshes with a gear 21 on a countershaft 22. The gear 21 also meshes 70 with a gear 23 on a shaft 24 which is substantially in alignment with the shaft 19. The shaft 24 is provided with a gear 25 which meshes with a gear 26 on the driving 75 shaft of a motor 27. The shaft 16 is connected through trains of gears with the winding spindles, which spindles are substantially the same in construction and operate in a similar manner as the spindles shown 80 in my prior Patents Nos. 952,282 and 992,692. These spindles, as shown in such patents are 85 forked to receive the fabric and when they are moved inwardly for engagement therewith, clutches are thrown into operation 90 which cause the spindles to rotate until the roll is completed, then as the spindles are 95 withdrawn to release the roll, the clutches are thrown out which causes the spindles to 100 stop rotation. In the present instance the shaft 16 is provided at one end with a gear 105 28 which meshes with a gear 29 on a countershaft 30. The gear 28 is free upon the shaft 16 but is adapted to be driven by means of a clutch 31 which is adapted to be 110 pressed into engaging position by means of a spring 32 which is acted upon by a yoke or slide 33 on a shift bar 34. The bar 34 is longitudinally movable in its bearings in the

frame and is connected at one end with a lever 35 (best seen in Fig. 2) which lever is pivoted to a bracket 36 from the frame and which is provided with a detent 37 which engages with the toothed segment 38 for holding the lever in adjusted position. Variable speed for the shaft 30 is provided by having a second gear 39 mounted on the shaft 16 which gear is of different diameter 10 from the gear 28 and which meshes with a gear 40 on the shaft 30. The gear 39 is also loosely mounted on the shaft 16 and is driven by means of a clutch 41 which is pressed into engaging position by means of 15 a spring 42 which engages with the slide 33 on the opposite side from the spring 32, the arrangement is such that when the shift rod 34, moves in one direction it will throw one of the clutches into operation and release 20 the other clutch, and when in central position both of the clutches will be out of engagement, and when moved in the other direction will cause the second clutch to operate.

The gear 40 meshes directly with a gear 25 43 on one of the clutch members 44 which turns one of the spindles 45. At the other end of the shaft 30 is another gear 46 which is of the same size as the gear 40 and which meshes with a second gear 43 on the clutch 30 member 44 for the second spindle. It will thus be seen that by means of this arrangement the speed of rotation of the spindles may be varied but the speed of the shaft 16 remains constant. The mechanism for reciprocating the spindles 45 is closely associated with the feeding and measuring mechanism which will now be described. The strip of paper or fabric such as indicated at 35 47 in Fig. 4, passes in between two rollers 48 and 49 at the top of the machine and then down into position to be engaged by the spindles. The roller 49 is mounted on a shaft 50 in fixed bearings in the frame, while the roller 48 is mounted in adjustable bearings 51 which are pressed downwardly by means of springs 52, the pressure of which may be adjusted by means of the nuts 53 so as to give any desired pressure between the rollers. The shaft 50 is provided at one end with a gear 54 which meshes with a gear 55 on a shaft 56, which shaft is provided at the opposite end with a disk 57, having an adjustable crank pin 58 mounted thereon. A convenient form for 50 such adjustment is clearly shown in Figs. 4 and 5, the pin being shown mounted in a slot 59 in the disk 57 and having its inner end engaging with a screw 60 whereby the distance of the pin from the center can be 55 accurately adjusted to vary the throw of the crank.

A crank rod 61 connects from the pin 58 to one end of a lever 62 which is pivoted at 63 to the frame and which carries an adjustable counterweight 64 at its opposite end,

such counterweight being for the purpose of balancing the weight of the crank rod and other connected parts. The lever 62 is connected by means of a link 65 to a rod 66 which rod moves in suitable guides in the frame and is connected at its lower end with a link 67 which in turn is connected with one end of a bell crank 68, best seen in Figs. 4 and 6. The bell crank 68 is pivoted on a shaft 69 in a casing 70 mounted in the lower 75 part of the frame. A ratchet wheel 71 is rigidly mounted on the shaft 69 and is turned by means of a spring pressed pawl 72 mounted on the other arm of the bell crank 68. A second spring pressed pawl 73 80 is mounted on the casing 70 and engages with the ratchet wheel 71 to prevent its backward movement. The shaft 69 also carries a cam 74 which is rigidly secured thereon. The cam 74 engages with a wheel 75 85 on a piston 76 in a cylinder 77 formed integrally with the casing 70 and presses this piston out against the tension of a spring 78 which is adjustably held in position by means of a threaded cap 79. In order that the piston 90 may have a quick return under the influence of the spring 78 a projection 80 is provided which extends from the piston 76 slightly beyond the wheel 75, so that it will remain in engagement with the cam momentarily 95 after the high part of the cam has left the wheel and will then drop or move into the low part of the cam as shown in Fig. 6. The piston 76 is adjustably connected with a bar 81 which reciprocates in suitable bearings on the main frame and which carries a tappet 82 which is pivoted at its outer end. This tappet is held in normal position by means of a spring 83 and the movement thereof, in either direction is limited by 105 shoulders or stops on the bar 81. The tappet 82 is adapted to engage with an arm or projection 84 on a locking lever 85, which lever is pivoted at 86 to a cylinder or casing 87 which is secured to the frame. This 110 lever is adapted to lock one of the operating cams in inoperative position. For this purpose it is provided with a catch or detent 88 which engages with a corresponding catch or detent 89 on a hollow piston 90 fitting 115 within the cylinder 87. The lever 85 is held in normal locking position by means of a spring 91. As shown in Fig. 6, the piston 90 is normally pressed toward the left by means of a spring 92. This tends to throw 120 the clutch 93 into operative position. This clutch may be of any ordinary or preferred form, but as shown, the cone member 94 is connected with the piston 90 which fits over the shaft 22 and such cone member is 125 keyed to the shaft so that it will be driven thereby. The cup member 95 of the clutch is connected directly with the gear 96 which meshes with a gear 97 on a short counter-shaft 98 which runs at right angles to the 130

shaft 22 and which is mounted in suitable bearings in the frame. The shaft 98 is provided with a gear 99 which meshes with a gear 100 of the same size, which gear 5 drives a second shaft 101 which is mounted adjacent to the shaft 98 as clearly shown in Fig. 10. These shafts are provided with right and left worms 102 and 103, the worm 102 being of twice the pitch as the worm 103. 10 The worm 102 meshes with a worm gear 104 which is loosely mounted on a shaft 105, having its bearings in the frame. The worm 103 meshes with the worm gear 106 which is also loosely mounted on the shaft 105 15 and which moves at half the speed of the gear 104. A face cam 107 is secured to, or formed integrally with, the worm gear 106 and engages with a pin or projection 108 on a piston or slide 109 which is slidably 20 mounted in the hub of the worm gear 104. This pin or projection is normally pressed toward the cam by means of a spring 110. A rod or pin 111 is slidably mounted within a tubular projection on the piston 109, 25 this rod being held in normal position by means of a spring 112. The outer end of the rod 111 is adapted to engage at times with a driving lug or projection 113 on a disk or wheel 114 which is securely mounted on the 30 shaft 105 and which is adapted to turn such shaft. The worm gear 106 is also provided with a trip finger or projection 115 (shown in Fig. 8) which is adapted to coact with certain parts to throw the clutch 93 out of 35 engagement. This finger or projection engages with the end of a lever 116 which is pivoted at 117 to the frame and which is provided at one side with a face cam 118. This cam engages with a roller 119 on the 40 end of a bar 120 which bar connects between parallel links 121 and 122, these links being pivoted at their upper ends to suitable bearings on a rod 123, which rod is securely fastened in the frame. The lower end of the 45 link 122 is provided with pins or trunnions 124 which pass through slots in the sides of the cylinder 87 and engage with the piston 90. This arrangement is such that when the cam or finger 115 strikes the free end of the 50 lever 116, it raises the lever and causes the face cam 118 to press against the roller 119 which swings the bar 120 to the right as shown in Fig. 6 and moves the piston 90 a sufficient distance to withdraw the cone 94 55 from the cup 95 and to permit the catch 88 to engage with the projection 89, which holds the clutch out of engagement. A cam or projection 125 is secured to the disk 114 (Figs 11 and 12) which engages 60 at times with the end of a bar 126 which bar is carried by links 127 and 128 pivoted to stationary portions of the frame. A discharge finger 129 is connected with the link 128, and a spring 130 is connected from this 65 link to a stationary part of the machine for

holding the connected parts in normal position. One or more fingers 129 may be provided, this being for the purpose of insuring the quick dropping or the discharge of the completed roll after the spindles have 70 been withdrawn. This arrangement is such that when the cam 125 strikes the end of the bar 126, the bar is moved upwardly causing the fingers 129 to engage with the completed roll and discharge the same. Then as soon 75 as the cam 125 has passed beyond the bar 126 the spring 130 returns the parts to normal position. A double cam 131 is secured to the shaft 105 and operates a lever 132 which is pivoted at 133 to the bottom of the 80 frame. One side of this cam engages with a roller 134 secured to the lever, while the other side engages with a flat projection 135 which permits a quick drop of the lever after the roller has passed from its portion 85 of the cam. The upper end of the lever 132 is connected to a link 136 which is pivoted to an arm 137 on a rocker bar 138, the ends of this bar being pivoted in suitable bearings in the frame. This rocker bar is provided 90 with arms 139 which are connected by means of links 140 with downwardly projecting arms 141 on rocker sleeves 142 which are pivoted on the main supports for the spindles. The arm 141 is also connected by means of a link 143 to a slide 144 which carries one of the cutting-off knives 145. The rocker sleeves 142 are also provided with upwardly extending arms or connections 146 which are connected by means of links 147 95 to a second slide 148 which carries the other cutting-off knife 149. This arrangement is such that the cam 131 will swing the lever 132 to the right as shown in Fig. 4 which separates the cutting-off knives. As soon 100 as the projection 135 passes the high part of the cam, a spring 150, which connects from the arm 137 to a stationary part of the frame, moves this arm to the left and swings the rocker bar 138. The connecting parts 105 cause the sleeves 142 to be rotated which in turn draws the knives 145 and 149 together 110 to cut off the material after the roll has dropped. The shaft 105 is provided at either end 115 with cam wheels 151 which engage with rollers 152 on the ends of the bars 153. These bars are pivoted to links 154 and 155 which are pivoted at their lower ends to suitable bearings in the lower part of the frame. The links or levers 155 extend upwardly and are connected at their upper ends by means of links 156 with the slidable heads which carry the spindles 45. This 120 arrangement is such that, at the proper time, the upper ends of the levers 155 will swing outwardly as indicated in Fig. 1, which will withdraw the spindles 45 from the completed roll and will then move inwardly to cause 125 the spindles to again engage with the fabric. 130

The operation of the machine is as follows: The paper or other fabric to be reeled is passed between the rollers 48 and 49 as shown in Fig. 4, and down through the slots 5 in the spindles 45. Then the lever 35 (Fig. 2) is shifted from neutral position, either to the right or left, depending upon the desired speed for the spindles. This throws one of the clutches 31 or 41 into engagement 10 as the case may be. The motor 27 having been started, will drive the shaft 16 so that the throwing in of such clutch will cause the intermediate shaft 30 to be driven and this in turn causes the spindle revolving 15 clutches to be turned, thereby revolving the spindles. As soon as the spindles start to turn they begin to wind up the fabric into a roll, and consequently draw the fabric between the rollers 48 and 49, the latter being 20 preferably made of suitable material or provided with a suitable covering, such as rubber, so as to insure these rollers being positively turned with the same peripheral speed, as the speed of the fabric passing thereover. 25 This is, in fact, the measuring roller and directly controls the cutting-off action. As the roller 49 revolves, it turns the shaft 56 which turns the disk 57 with the adjustable crank thereon. As this crank is turned it 30 reciprocates the rods which connect it with the bell crank 68 and causes this crank to be swung on its pivot. The movement of the crank causes the pawl 72 to rotate the ratchet wheel 71, which in turn drives the cam 74 in 35 the direction indicated in Fig. 6. This cam gradually presses against the roller 75 and moves the piston 76 to the right against the tension of the spring 78 until the tappet 82 passes beyond the finger or projection 84 on the lever 85. As the high part of the cam 40 is reached it engages with the projection 80 so that when it passes the projection, the spring 78 will quickly force the piston 76 back to original position. This causes the 45 tappet 82 to strike against the projection 84 which raises the outer end of the lever 85 until the catch 88 releases the piston 90. This permits the spring 92 to quickly force the clutch 95 into operation. This clutch 50 then drives the shaft 98 (Fig. 10) through the gears 96 and 97 and this in turn drives the shaft 101 through the gears 99 and 100. This causes the worms 102 and 103 to drive the worm gears 104 and 106. As the gear 55 104 moves at twice the speed of the gear 106, the pin 108 engages with the face cam 107 and forces the piston 109 to the left as shown in Fig. 11, which causes the pin 111 to engage with the driving lock or projection 113 60 on the disk 114. If such pin moves toward the left at the time it is opposite the projection, the spring 112 permits the piston to be moved until the pin 111 passes the projection when the spring 112 will force the pin into 65 position to engage with the side of the lock

113. This causes the shaft 105 to be driven, which turns the cam wheels 151 and this swings the arms 155 out, thereby withdrawing the spindles from the completed roll. As soon as the spindles are free from the roll 70 the discharge fingers 129 are swung downwardly through the action of the cam 125, thereby causing the roll to quickly drop onto the discharge chute 157 (Fig. 4). In some instances these discharge fingers may not be 75 necessary as the roll will drop through the action of gravity, although they may be desirable when the machine is operated at a high speed. As soon as the roll drops, the double cam 131 releases the lever 132 so that 80 the spring 150 may actuate the cutting off knives which are caused to co-act and cut off the fabric just below the spindles. Such paper or fabric is preferably held by means of guides such as shown in my former patents. 85

As soon as the completed roll drops and the paper or fabric is severed, the levers 155 again move inwardly to cause the forked spindles to again engage with the paper or 90 fabric preparatory to winding the next roll. At about the time the spindles return to operative position and start to wind the next roll the cam or projection 115 raises the end of the lever 116 which acts through 95 the connecting parts to throw the clutch 95 out of engagement, which places the parts again in substantially the same position as when starting. It will thus be seen that substantially the whole machine, with the exception of the spindles, is directly operated or controlled by the fabric passing over the roller 49. In other words the time required for one revolution of the cam 74 which actuates the discharge in cut-off 100 mechanism is directly dependent upon the number of turns of the roller 49, and by adjusting the crank pin 58 the throw of the pawl 72 may be regulated so that the cam will make a complete revolution when the 110 roller 49 has made any desired number of turns. It will thus be seen that this provides an exceedingly accurate measure for measuring the amount of paper or fabric in each roll, and the amount to be placed 115 in each roll may be readily varied within the limits of the adjustment of the machine. As the operation of the stopping, cut-off and discharge mechanism depends upon the paper or fabric which is being rolled, it is 120 often desirable that these parts shall operate as easily as possible and without putting any undue load on the roller 49 so that the weight 64 which serves to balance the rods and other parts connected with the adjustable crank is a desirable feature as it relieves 125 the paper of a certain amount of strain.

The operation of the machine by means of the fabric, which is being wound into rolls also serves another exceedingly useful 130

purpose as, if the paper is torn so that it cannot operate the roller 49, the machine will stop operation until it is again properly set. In such case, or if the operator 5 notes any defect in the paper and desires to cause the stopping and discharging mechanism to act before ratchet wheel 71 is turned by the normal operation of the machine, he can turn the cam 74 by means 10 of a hand wheel or knob 158 on the shaft 69 to which such cam is rigidly attached. It will also be noted that the measurement of the paper or fabric by its turning the roller 49 gives substantially an absolutely accurate 15 lineal measurement, regardless of the thickness of the paper or fabric which is being acted upon.

Having thus described my invention which, however, I do not wish to limit to the 20 exact arrangement or details of construction herein shown and described, except as set forth in the appended claims, what I claim and desire to secure by Letters Patent is:

25 1. In a machine for winding rolls of paper or the like from a continuous strip of material, the combination of a winding mechanism, stopping mechanism for stopping the winding mechanism, severing mechanism, a member actuated by the material to be wound for controlling the stopping mechanism, and means for automatically starting the winding of a new roll, the arrangement being such that the device will continuously 30 and automatically wind and sever complete rolls from the material.

2. In a machine for winding rolls of paper or the like from a continuous strip of material, the combination of winding means, automatic starting and stopping means for said winding means, severing means for severing the material, and means actuated by the material for measuring the amount of material to be wound in a roll, and for controlling said stopping mechanism, whereby 45 the machine will continuously and automatically roll and sever complete rolls from the strip of material.

3. In a reel or winding machine, the combination of winding spindles, means for turning said spindles for winding the fabric, means for stopping said spindles and withdrawing them from the completed roll, means for cutting the fabric after the roll 50 is completed, and means actuated by the fabric for controlling said stopping means and cutting off means.

4. In a reel or winding machine, the combination with mechanism for automatically winding a series of rolls from a continuous strip of material and cutting off each of said rolls when completed, of a roller over which the material is drawn, means actuated by said roller for controlling the winding and cutting off devices, and means for

automatically starting and completing the winding of a new roll after one has been completed, and severing from the supply strip.

5. In a reel or winding machine, the combination of spindles for engagement with paper or the like to be wound, means for turning said spindles, means for withdrawing said spindles from the completed roll and again returning them for engagement 70 with the paper, means for cutting off the paper after the roll is completed, a roller driven by the paper as it is wound on the spindles, a clutch for starting and stopping the spindles, withdrawing and cutting-off 75 mechanism, and connections between said roller and said clutch for throwing the clutch into engagement when the roller has made a predetermined number of turns.

6. In a reel or winding machine, the combination of a pair of forked spindles for engagement with the material to be wound, means for turning said spindles, means for reciprocating said spindles, means for cutting off the paper below the spindles after a 80 roll has been completed and dropped, a roller over which the material to be wound is drawn, and adjustable connections between said roller and said reciprocating and cutting-off devices, whereby the action of said 85 devices is controlled by said roller.

7. In a reel or winding machine, the combination of a shaft, a pair of gears on said shaft, means for driving said gears, one of said gears being turned at twice the speed of 100 the other, a cam on the slow moving gear, a plunger in the fast moving gear having one end adapted to engage with said cam, a driving member secured to said shaft with which the other end of the plunger will engage for turning the shaft, a spring for holding said plunger normally out of engagement with the driving member, cams on 105 said shaft, levers actuated by said cams, and spindles connected with said levers and 110 reciprocated to be reciprocated thereby.

8. In a machine of the character set forth, the combination of a shaft, a worm on said shaft, a second shaft, means for turning said shafts at the same speed, a worm on the second shaft, said second named worm being of half the pitch as the first worm, a third shaft, a pair of worm gears loosely mounted on said third shaft driven by said worms, a face cam on the slow moving gear, a plunger 115 arranged at right angles to the fast moving gear and having one end engaging with said cam, a spring tending to hold said plunger in engagement with the cam, a driving disk on said third named shaft, having a projection 120 adapted to be engaged by the opposite end of said plunger for turning the shaft, the arrangement being such that when the plunger is moved longitudinally a sufficient distance by the face cam it will engage said 125 130

projection and turn the last named shaft until it is released by the cam and thrown out of engagement with the projection on the driving disk.

- 5 9. In a reel or winding machine, the combination with the winding spindles, of sleeves or rings mounted concentrically with said spindle, knife carrying slides arranged on either side of said spindles, connections between said sleeves and said slides for moving the slides when the sleeves are rotated and means for rotating said sleeves.
- 10 10. In a reel or winding machine, the combination of means for winding rolls from strips of fabric, cutting off knives for severing the fabric after a roll is completed, a pair of slides for carrying the cutting-off knives, oscillating arms pivotally mounted between said slides, connections between said arms and said slides for moving the slides toward and away from each other, a spring tending to move said arms to cause the knives to approach each other, and cam actuated means for holding said slides in normally separated position.
- 15 11. In a reel or winding machine, the combination of a roller adapted to be driven by the material to be wound, an adjustable crank driven by said roller, a ratchet wheel
- 20 30 35 driven by said crank, a cam actuated by said ratchet wheel, a clutch for controlling the spindle starting and stopping mechanism, a spring tending to throw said clutch into engagement, a catch for holding said clutch out of engagement and means operated by said cam for tripping said catch.

12. In a reel or winding machine the combination of a pair of rollers between which the material to be wound is drawn, means for adjusting the pressure between said rollers, an adjustable crank driven by one of said rollers, a ratchet wheel, connections between said crank and said wheel for turning the wheel, a cam driven by said ratchet wheel, a piston actuated by said cam, a spring for returning the piston to normal position, a trip actuated by said piston, a clutch for controlling the mechanism for completing and starting a roll, a spring tending to throw said clutch into engagement, a latch for holding said clutch out of engagement, said latch being operated by the trip to throw the clutch into engagement, and means for automatically throwing said clutch out of engagement.

- 40 45 50 55 60 13. In a machine for continuously winding and severing a plurality of rolls from a strip of fabric, the combination of winding spindles, means for causing said spindles to engage with and to be disengaged from the fabric, means for turning said spindles to wind the rolls, a measuring roll operated by the strip of fabric, and means operated by said measuring roll for controlling the movements of the spindles.

ANTON SKOFSRUD.
